UNITED STATES PATENT OFFICE.

SAM KITZES, OF NEW YORK, N. Y.

SAFETY-RAZOR.

1,089,228.

Specification of Letters Patent.

Patented Mar. 3, 1914.

Application filed July 8, 1913. Serial No. 777,852.

To all whom it may concern:

Be it known that I, SAM KITZES, a citizen of the United States, and a resident of the city of New York, borough of Manhattan, in the county and State of New York, have invented a new and Improved Safety-Razor, of which the following is a full, clear, and exact description.

The object of the invention is to provide a new and improved safety razor of the flexible blade type, arranged to permit of conveniently and quickly assembling and disassembling the parts, and to provide a detachable gathering receptacle for the lather.

For the purpose mentioned, use is made of a frame provided at the top with a guard, a razor blade resting on the said guard, a backing overlying the said razor blade and provided with a fixed rod having a threaded end, a lather-receiving receptacle detachably held on the said frame, the said razor blade, the said guard, the said frame bottom and the said receptacle having registering apertures for the passage of the said rod, and a handle screwing on the lower end of the said rod and abutting against the under side of the said receptacle to fasten the several parts together.

A practical embodiment of the invention is represented in the accompanying drawings forming a part of this specification, in which similar characters of reference indicate corresponding parts in all the views.

Figure 1 is a sectional side elevation of the safety razor; Fig. 2 is a like view of the same with the parts disassembled; and Fig. 3 is a cross section of the safety razor.

The frame A of the safety razor is formed of a bottom A', end bars A² rising from the said bottom A', and a guard plate A³ attached to the upper ends of the bars A², as plainly indicated in the drawings. The guard plate A³ is curved in a transverse direction and is provided at the front and rear edges with teeth A⁴ forming guards. A flexible razor blade B is adapted to rest on the top of the guard plate A³ and the cutting edges of the razor blade B extend to within a short distance of the points of the teeth A⁴ so that the latter form a proper guard for the cutting edges. A backing C curved in a transverse direction is adapted to overlie the razor blade B, and the said backing C is provided with lugs C' extending through apertures B' formed in the razor blade B and also extending through

apertures A⁵ formed in the guard plate A³. By the arrangement described the razor blade B is held properly on the guard plate A³ at the time the parts are assembled.

The backing C is provided at its middle with a depending rod D extending loosely through an aperture B² formed in the razor blade B and also passing through apertures A⁶, A⁷ formed in the guard plate A³ and the bottom A' of the frame A.

A lather-receiving receptacle E in the form of a trough is removably held on the bottom A' of the frame A, and the bottom of the receptacle E is provided with an opening E' through which is adapted to pass the lower threaded end D' of the rod D, to permit the user to screw a handle F onto the threaded end D' with a view to fasten the several parts together, and to draw the backing C downward with a view to curve the flexible blade B on the guard plate A³, and to securely fasten the receptacle E in position on the under side of the bottom A' of the frame A. The bottom A' is provided at the front and rear with upwardly-extending struck-up lugs A⁸ on which rest lugs E² struck up from the front and rear of the receptacle E and bent inwardly so as to engage the lugs A⁸ at the top on sliding the receptacle E sidewise into position on the frame A, as plainly indicated in Figs. 1 and 3. When the parts are to be assembled, the receptacle is slid sidewise on the bottom of the frame until the lugs E² of the receptacle engage and rest on the lugs A⁸ of the bottom. The receptacle, which is on the outside of the bottom of the frame, is thus held on the frame and when the receptacle is in this position the openings in the bottom of the frame and the receptacle are in register for the passage of the threaded end of the rod D. It is understood that on screwing up the handle F on the threaded end D' of the rod D, the receptacle E is firmly fastened in position and endwise movement thereof is prevented.

When it is desired to disassemble the parts for removing the razor blade, the user unscrews the handle F from the threaded end D' of the rod D to permit of lifting the backing C off the blade B and to disengage the rod D from the frame A to allow removal of the razor blade B and also sidewise removal of the receptacle E from the frame A. The several parts can then be readily cleaned, replaced and fastened to-

gether by screwing the handle F on the threaded end D' of the rod D.

The safety razor shown and described is composed of comparatively few parts and 5 when in use the lather readily passes into the receptacle E which thus forms a shield for the hand holding the safety razor.

Having thus described my invention, I claim as new and desire to secure by Letters Patent:

1. A safety razor, comprising in combination a frame provided at the top with a guard, a blade resting on the said guard, a backing overlying the said blade and provided with a fixed rod having a threaded end, a lather-receiving receptacle detachably held on the bottom of the said frame, the said blade, the said guard, the said frame bottom and the said receptacle having registering apertures for the passage of the said rod, and a handle screwing on the lower end of the said rod 40 and abutting against the under side of the said receptacle to fasten the several parts together.
2. A safety razor, comprising in combination a frame provided at the top with a guard, a blade resting on the said guard, a backing overlying the said blade and provided with a fixed rod having a threaded end, a lather-receiving receptacle detachably held on the bottom of the said frame, the said receptacle being provided with inwardly-extending struck-up lugs and the bottom of the frame being provided with upwardly-extending lugs on which rest the

said receptacle lugs, the said blade, the said guard, the said frame bottom and the said receptacle having registering apertures for the passage of the said rod, and a handle screwing on the lower end of the said rod 40 and abutting against the under side of the said receptacle to fasten the several parts together.

3. A safety razor provided with a frame having a bottom, a lather-gathering receptacle held sidewise removable on the bottom of said frame on the outer face thereof, the bottom of said frame and the said receptacle being provided on the front and rear with lugs in engagement with each other, to 45 hold the receptacle in position on the frame, and means fastening the receptacle to the said frame.

4. A safety razor provided with a frame, a lather-gathering receptacle of trough 55 shape and provided with inwardly-extending lugs, the frame having a bottom provided with upwardly-extending lugs engaged by the said receptacle lugs, end bars rising integrally from the said bottom, and a guard plate held on the upper ends of the said end bars.

In testimony whereof I have signed my name to this specification in the presence of two subscribing witnesses.

SAM KITZES.
